TREE STANDS

Ian F. Norton, Toronto, Ontario, Canada, assignor to
Noma Lites Canada Limited, Scarborough, Ontario,
Canada

Filed Feb. 24, 1971, Ser. No. 118,591

Term of patent 14 years

Int. Cl. D6—99

U.S. Cl. D6—105

FIG. 1.

FIG. 2.

FIG. 4.

FIG. 3.

FIG. 1 is an isometric view of a tree stand incorporating my new design;

FIG. 2 is a top plan view of the central portion thereof only;

FIG. 3 is a bottom plan view of the said central portion only, and

FIG. 4 is a fragmentary isometric view of portions of the leg and of the central socket in pre-assembly relation.

I claim:

The ornamental design for tree stands, as shown and described.
